FIG.2

Des. 189,161

PAGE 3

FIG. 3

FIG.4

Figure 1 is a front perspective view of a radio receiver embodying my new design;

Figure 2 is a side perspective view;

Figure 3 is an enlarged top plan view; and

Figure 4 is an enlarged side elevational view thereof, the side not shown being substantially the same in appearance as the side shown.

I claim:

The ornamental design for a radio receiver, substantially as shown and described.
